INTERNAL COMBUSTION ENGINE

Franciscus Cornelis Dons, Amsterdam,
NetherlandsApplication March 3, 1938, Serial No. 193,636
In the Netherlands March 30, 1937

1 Claim. (Cl. 123—51)

The present invention relates to internal combustion engines of the kind comprising two working cylinders arranged side by side, there being two oppositely working pistons in each cylinder, and the movement of the four pistons being transmitted to a common shaft. It is known in connection with engines of this type to use either the outermost spaces between the covers of the cylinders and the pistons, or the innermost 10 spaces between the said members as combustion chambers, and to transmit the movement of the pistons to a common shaft by linkage arranged entirely outside the cylinders, said linkage being connected with pins or projections of the pistons 15 guided in slots of the cylinder sides projecting on the outside through these slots.

Engines of this type may be worked either as two or four-stroke engines.

The object of the present invention is to provide an improved, simplified and very compact engine of the above type. With this object in view, I have devised an internal combustion engine with two cylinders arranged side by side and parallel to one another, two oppositely working pistons in each cylinder, one combustion chamber at each end of each cylinder and one combustion chamber between the two pistons in each cylinder, each piston being provided with outwardly projecting pins, transverse members 25 connecting corresponding pins, a crank shaft arranged between said cylinders parallel to said pins, and connecting rods connecting said transverse members with cranks of said crank shaft.

The two pins of each piston may obviously be 35 substituted by a single transverse rod passing through the cylinder and guided in slots. The pins or the transverse rod replacing same are fixed to the pistons after the latter have been inserted in the cylinder. Each cylinder, and in 40 some cases both cylinders, may be constructed as an integral block, the whole construction being particularly suitable for small engines. Several units, each comprising two cylinders with four pistons, may be arranged side by side to form a 45 single engine. The arrangement of the cylinder, the pistons and the transmission gear is such that the weights of the movable parts are completely balanced.

One construction embodying the features of 50 the invention as applied to a two-stroke engine, is shown by way of example in the accompanying drawing, in which:

Fig. 1 is an elevation of the engine, one cylinder and one piston being shown in section, and

Fig. 2 a section on line II—II of Fig. 1, a part

of the cylinder being broken away to show a piston.

Referring to the drawing, 1, 2 indicates the first cylinder and 3, 4 indicates the second cylinder. These cylinders are arranged parallel to one another side by side and are rigidly connected by cast on members 5 and 6, the latter members serving at the same time as bearings for a crank-shaft 7. Each cylinder is provided at the ends with covers 8, 8 fitted with atomisers 9, 9, and 10 with an atomiser 10 in the central position corresponding to the intermediate combustion chamber thereof. In each cylinder there are two pistons, each piston having two ends 11 and 12 connected by a connecting body 13. The arrangement is such that each cylinder is provided with three combustion chambers, namely one inner chamber formed between and common to the ends 12 of the pistons and one chamber at each outer end of the cylinder for the end 11 of each 20 piston. The piston ends 11 and 12 are as usual provided with piston rings 16 and 17. In each connecting body 13 are fixed pins or projections 14 which extend outside the cylinders through slots 15 formed in the cylinder sides, and are provided for the purpose of connecting each pin to a transverse member 18 or 19 (one pair of pins being connected to member 18 and the other pair to member 19), which members are themselves connected by means of rods 20 and 21 which 25 transmit the movement of the members 18 and 19 to the crank shaft 7 through the medium of connecting rods 21 and 28 respectively, the said rods 21 and 28 on either side working upon a double crank of the shaft 7 as shown. It will be 30 seen that the distance between the cylinders is very small and that the masses of the moving parts are completely balanced. Ports 22 and 23 are provided for the inlet and outlet of the gases into and from the working spaces at the ends of 35 the cylinders, whilst ports 24 and 25 are provided for the inlet and outlet of the gases into and from the inner working spaces between the adjacent ends of each two pistons. In order to provide sufficient bearing surface for the pins 14, the 40 cylinder walls are provided with thickened portions or guides 26 around the slots. It will be understood that instead of two pins fixed to the cylinder, a single rod passing through the body 13 could be used. Any suitable cooling means such 45 as is commonly used in internal combustion engine practice may be provided.

The operation is as follows:

After the engine has been started, the pistons 50 on moving from the position shown towards the 55

cylinder covers close by means of their outer ends the outlet ports, whereupon air is compressed. During this movement the pistons open by means of the inner ends the ports 24 and 25 causing combustion gases to be expelled and fresh air to be drawn in. Upon the pistons nearly reaching their outer positions and the compression being a maximum, fuel is injected through the nozzles or atomisers 9 and is either automatically ignited 10 owing to the high temperature occurring, or is ignited by means of ignition plugs. In each space between the two pistons of a cylinder, the same working operation takes place as at the cover ends of the cylinders, fuel being injected 15 through nozzles 10. During the return movement the pistons expel the combustion gases through ports 23 and draw in fresh air through ports 22. The reciprocating movement of the pistons is transmitted by means of the pins 14 projecting 20 through and guided in the slots 15, to the transverse members 18 and 19. The latter are connected by the connecting rods 21 and 28 each with a double crank of the crank shaft so that the power of the four pistons is transmitted to the 25 crank shaft in a very simple manner, the cranks of oppositely arranged pistons being displaced

through an angle of 180°. It will be evident that with this arrangement after each half revolution an explosion occurs, so that each piston is driven by the force of an explosion from one end position to the other. 5

If the invention is applied to a four-stroke engine, it will, of course, be necessary to provide control valves for the inlet and outlet ports.

I claim:

In an internal combustion engine the combination of: two cylinders arranged side by side and parallel to one another, two oppositely working pistons in each cylinder; and each cylinder having one combustion chamber at each end thereof and a third combustion chamber between the 15 adjacent ends of the pistons therein; each piston being provided with outwardly projecting pins; transverse members connecting the pins of each piston in one cylinder with the corresponding pins of the corresponding piston in said other cylinder; 20 a crank shaft arranged externally of and between said cylinders parallel to said pins; and connecting rods connecting said transverse members with cranks of said crank shaft.
